United States Patent Office

Des. 178,619
Patented Aug. 28, 1956

178,619

SCOOTER

Roger Tonelli, Chicago, Ill.

Application March 14, 1956, Serial No. 40,607

Term of patent 14 years

(Cl. D34—15)

FIG. 1

FIG. 2

I claim:

The ornamental design for a scooter, as shown.
